UNITED STATES PATENT OFFICE.

ALBERT E. BOOKWALTER AND MAX A. DORLAND, OF COEUR D'ALENE, IDAHO.

ORE-SEPARATOR.

1,083,481.

Specification of Letters Patent.

Patented Jan. 6, 1914.

Application filed May 24, 1913. Serial No. 769,736.

To all whom it may concern:

Be it known that we, ALBERT E. BOOKWALTER and MAX A. DORLAND, citizens of the United States of America, and residents of Coeur d'Alene, in the county of Kootenai and State of Idaho, have invented certain new and useful Improvements in Ore-Separators, of which the following is a specification.

10 This invention relates to improvements in that class of ore separators shown in our Patent No 1,058,349, granted April 8, 1913.

The object of this invention is to improve that type of ore separator and to provide 15 means for regulating the force of the water to suit the particular material being operated upon.

The invention consists in the construction and arrangement of parts hereinafter more 20 particularly described and then definitely pointed out by the claims at the end thereof.

In the accompanying drawings which, it will be understood represent the preferable embodiment of our invention, Figure 1 is a 25 side elevation with the main parts in section of a separator made in accordance with our invention. Fig. 2 is a perspective view of one of the screen trays. Fig. 3 is a top plan view of the plunger. Fig. 4 is a top plan view of a valve board. Fig. 5 is a perspective sectional view through line A—B of Fig. 3. Fig. 6 is a similar view through the line C—D of Fig. 4. Fig. 7 is a vertical cross section through part of the screen compartment. Fig. 8 is a perspective view of 30 one of the frames in the screen compartment. Fig. 9 is a longitudinal section through the screen compartment.

Referring now to the details of the drawings by numerals: 1, 2, 3 and 4 represent the 40 main frame of the machine which may be constructed in any desired manner, the members 2 and 4 being connected together by bolts 5. Between the vertical members 1 and 3 are supported side boards 7 and 9, a center or partition 11 being provided, leaving a plunger side and a screen side on opposite sides of said partition.

13 and 14 represent linings in the plunger 45 compartment between which is located the plunger 15. The plunger is provided with a plunger rod 16 operated in any desirable manner. Located at the bottom of the plunger compartment and between the linings 13 and 14 is a valve board 18. The plunger has openings provided therein each

of which is fitted with a valve of the character shown in Fig. 5, each opening in the plunger having, as shown in said figure, a lining 20 provided with supporting cross bars 22 through the center of which passes a rod 24, on the bottom of which is secured a valve 26. Each end of the rod 24 is provided with an adjusting device as 27 and 28, a spring 30 being provided, the tension of which may be changed by adjusting either of the devices 27 or 28 as occasion may require. The valve board at the bottom of the plunger compartment is provided with a series of openings, each of which contains a lining 32 similar to the linings 20 in the plunger. Each lining 32 is provided with a valve 34 whose spindle 36 passes downwardly through the downwardly projecting frame 38, the spring 40 being provided to 50 normally hold the valve 34 in its closed position. The valve board 18 also has an additional opening 42 which is provided with a flat valve 44 connected to an operating rod 46 provided with a crank 48 at its upper 55 end, the plunger being provided with a recess 50 on one side thereof to accommodate the operating rod 46. The construction is such that the operator may open or close the flat valve 44 by moving the crank 48 from the exterior of the machine, as may be desirable. The upper end of the plunger compartment is provided with a cover 52. Through this cover 52 enters a feed pipe 54 for each section of the machine, this pipe being fed from a common pipe 56, a valve 58 being provided to control the feed through the pipe 54. The plunger compartment and the screen compartment have a common bottom formed by angular boards 60 and 62 60 supported by angle pieces 64 and 68; the angular boards 60 and 62 forming a hopper bottom provided with a valve 70 through which the product may be withdrawn.

In the screen compartment, we support a 100 deflector tray 80 upon cleats 82, this deflector tray being like that shown in our aforesaid Patent No. 1,058,349 and therefore is provided with deflectors 84 operated by a common connecting rod 86 (see Fig. 1). 105 Underneath this deflector tray, we locate a diagonally disposed emergency screen 90, arranged to catch the balls in case the ball screen breaks. The ball screen just referred to is designated by the numeral 92 and may 110 be identical with that shown in our aforesaid patent, and therefore comprises a screen

94 upon which are supported a series of balls 96. Immediately over the ball tray 92, we locate a supplemental screen tray 98 which is shown in perspective view in Fig. 2 and is provided with a screen 100 on its upper surface supported at its center by a partition 102. This supplemental screen tray rests upon the top of the ball tray, as shown in Fig. 1, and the screen is fastened to the top 10 of the tray, as shown in Fig. 2, the stock being fed into the machine on top of this screen 100. The screen allows the sand and finer particles of material to pass through onto the bed of balls while the gravel is held 15 upon the screen and worked along the screen compartment and discharged into the next screen compartment until it is thrown out with the tailings. The purpose of this screen 100 is to enable the stock admitted 20 into the machine to work through faster, and besides it is not necessary to remove all the gravel before being admitted. The gravel does not work well if allowed to come in contact with the balls supported on the 25 screen below, and by the use of this screen 100 coarser stock can be used. The frame of this supplemental tray 98 corresponds with the frames of the other trays, and as above stated, rests upon the ball tray 92 and supports the riffle tray 104, to be described. 30 The discharge end of the supplemental tray is inclined, as illustrated in Fig. 2, so as to hold back a thin bed of gravel in order that the sand and fine particles will be washed 35 off and down through the screen onto the layer of balls. The riffle tray 104, located above the supplemental tray, is trimmed down to fit this incline.

The riffle tray 104 which has been described 40 as being supported upon the supplemental tray 98 is shown in perspective view in Fig. 8 and on an enlarged scale, in cross section, in Fig. 7. Generally speaking, this riffle tray is like that shown in our previous 45 patent, in that it has a number of riffles 106 pivotally supported by the side walls of the riffle tray, the bottoms of these riffles having secured to them a common connecting strip 107 so that the riffles are operated in unison. 50 Also similar to our aforesaid patent, the riffle tray is provided with dam boards 108 but in addition to the parts shown in our aforesaid patent the riffle tray is provided with a slime tube 110, shown particularly in 55 Figs. 7 and 8. This slime tube is supported by the sides of the riffle tray and is slotted along its upper surface as indicated at 112 and has one end closed by a plug 114, shown in dotted lines in Fig. 7. Its other end is 60 open so that the material passing through the slot 112 may pass out through the open end of the slime tube, through the wall of the riffle tray, into an opening in the outer wall 3, from whence the material may be discharged through a discharge pipe 116, see 65

Fig. 7; the wall of the riffle tray being provided with a rubber gasket 119, shown in Fig. 8, to afford a tight joint between the riffle tray and the side wall of the screen compartment. The slime tube 110 is provided with a lever or handle 118 by which the slime tube may be slightly rotated to change the position of the slot 112. In other words, by moving the lever 118, the slime tube is rotated so as to raise or lower the slot as may be desirable. The riffles 106 force the stock down into and below the water as it is passed along through the machine, the bottoms of these riffles holding the stock down near the bottom of the tray, 80 while the tops of the riffles extend above the water and act with the dam boards to prevent the fine particles from floating through without being submerged. The slime tube is located directly in front of one of the dam boards so that the slime may be washed into the slime tube through its slot 112 and carried by the water through the connection and discharged into any suitable receptacle. 85 In order to prevent the slime from clogging the tube, we prefer to employ a twisted wire 120 which is connected with the agitator eccentric in such a manner that as the eccentric operates to give motion to the plunger rod, the wire or rod 120 will be kept in motion and thus prevent the slime from clogging the tube 110. 90

Generally speaking, the construction of our device will be seen to be very similar to that shown in our aforesaid patent, but owing to the use of the valves in the plunger and valve board, and the use of the slime tube and the supplemental screen tray, the action is somewhat different. In ordinary jigs, the action of the water under the stock being worked is in an up and down motion, and it is upon the precipitating action that the work of a common jig depends. In our machines, we desire in some classes of ore a more steady upward pressure of the water. 100 Of course the plunger gives the water an intermittent upward pressure but the valve arrangement is to do away with all or part of the up and down alternate motion. By using the suction valves, we are enabled to use the same property of a common jig plunger to any extent we wish, but we can cut out the down suction of the water, wholly or in part, as we see fit, by opening or closing the valve 44, shown best in Fig. 4. The 110 arrangement may be illustrated by a glass tube. If such a tube of, we will say, one inch in diameter is connected with a water hydrant by means of a hose and held in a vertical position, we get just such an upward pressure of water as we desire in our machine. Now, if sand containing mineral is sprinkled upon this water, the heavier material will precipitate itself against greater pressure than the lighter sand, and this water pressure can 120 125 130

be regulated by the valve on the hydrant, and the separation be made, the mineral going to the bottom of the tube and the sand being washed over the edge of the tube.

5 Now, our valve arrangement gives to this upward pressing column of water a more steady upward pressure than is given in jigs of common arrangement; and if in some cases we find it desirable to use downward

10 suction, we can get the same by opening the suction valve 44 by means of the operating rod 46 and its crank or handle 48. The purpose of the supplemental screen tray is for use more particularly in placer work than in

15 ore. It enables the machine to handle coarser stock and stock containing gravel that could not be used otherwise. This screen holds the gravel on top and does not allow it to drop down in contact with the

20 bed of balls, and the sand which is dropped through is worked the same as though this screen were not in the machine, the tailing sand being held up and worked along the top of the balls and discharged through the

25 aperture below the screen. By the use of the slime tube, we are enabled to save the slimes by skimming it off the top of the water on which it floats instead of precipitating it. There is a certain amount of

30 value lost in slimes by reason of its floating off, and our slime tubes combined with the riffles shown in our aforesaid patent, remove this slime and deposits it in a receptacle where it is settled and sacked as a concentrate.

It is obvious that changes may be made without departing from the spirit of our invention, the scope of which is set forth by the appended claims. For example, it will

40 be manifest that valves of different arrangement and construction may be used.

What we claim as our invention is:

1. In apparatus of the character described, the combination of a screen compartment

45 and a plunger compartment, a plunger and valve board and self-acting valves located in said plunger and valve board, the valve board also being provided with a manually controlled valve, substantially as described.

50 2. In apparatus of the character described, the combination with a screen compartment

and a plunger compartment, the plunger compartment having a plunger therein and a valve board; the plunger being provided with a series of valves opening upon the 55 upward movement of the plunger, and the valve board being provided with a series of valves opening upon the downward movement of the plunger, the said valve board also being provided with a manually controlled valve, substantially as described. 60

3. In apparatus of the character described, a screen compartment and a plunger co-acting therewith in combination with a screen in said compartment and balls located on 65 said screen, and a supplemental screen located over the said ball screen and having its discharge end inclined upwardly, substantially as described.

4. In apparatus of the character described, 70 a screen compartment, in combination with a rifle tray arranged in said screen compartment and having a slime tube extending across the same in a horizontal position with an opening therein substantially at the 75 height of the liquid, whereby the slime is carried off of said liquid, said horizontal tube being adjustable on its axis, so that the position of said horizontal tube and its opening may be raised or lowered as the height 80 of the liquid is varied, substantially as described.

5. In apparatus of the character described, 85 a plunger compartment, a plunger and means for operating the same, in combination with a screen compartment, a rifle tray arranged in said screen compartment and having a slime tube located horizontally therein substantially at the level of the liquid, said tube having an opening extending 90 longitudinally therein through which the slimes enter, a discharge for said tube, and a cleaning out device in said tube operated from the same means that operate the aforesaid plunger, substantially as described. 95

In testimony whereof we affix our signatures in presence of two witnesses.

ALBERT E. BOOKWALTER.
MAX A. DORLAND.
